CLAIM

The ornamental design for a video communications terminal, including housing, telephone handset, keyboard camera and image screen.

DESCRIPTION

FIG. 1 is a front, top and right side perspective view of a video communications terminal, including housing, telephone handset, keyboard camera and image screen showing our new design;

FIGS. 2 and 3 are respectively front and rear elevational views thereof;

FIGS. 4 and 5 are respectively right and left side elevational views thereof;

FIGS. 6 and 7 are respectively top and bottom plan views thereof; and

FIG. 8 is a perspective view thereof with the camera member rotated to the front image screen member of the housing.
